UNITED STATES PATENT OFFICE.

LEVERETT D. CAMPBELL, OF LATONIA, KENTUCKY, ASSIGNOR TO THE GLOBE FOLDING BOX COMPANY, OF CINCINNATI, OHIO, A CORPORATION OF OHIO.

DISPLAY CARTON.

Application filed December 5, 1921. Serial No. 519,903.

To all whom it may concern:

Be it known that I, LEVERETT D. CAMPBELL, a citizen of the United States, and a resident of Latonia, in the county of 5 Kenton and State of Kentucky, have invented certain new and useful Improvements in Display Cartons, of which the following is a full, clear, and exact description, reference being had to the accompanying 10 drawings, forming part of this specification.

The object of my invention is to provide a collapsible, knock-down carton made from suitable cardboard or other material with 15 the cover and body of the carton formed of a single, integral blank, so cut and scored that it may be readily and easily folded into box and cover and the body of the carton inserted within the cover to rest on 20 one end for display purposes with an integral flap also provided, adapted to be turned back for display advertisement.

The special object is to cut the blank, so that there shall be very little waste of material, while providing a construction that can be set up into a complete box and cover 25 quickly and with great ease and in which the cover can be removed and seated under the box for display purposes with a single 30 movement and as readily and easily returned to close the box.

In the accompanying drawings,

Figure 1 is a plan view of the blank from 35 which the collapsible box and cover are formed.

Figure 2 is a perspective view showing the blank partly folded.

Figure 3 is a similar view with the body 40 of the carton and the cover folded in finished form and with the box ready for filling.

Figure 4 is a longitudinal section of the box and cover with the cover partly enclosing the box.

Figure 5 is a similar section with the cover located under the box for display.

Figure 6 is a perspective view in display position.

The blank of cardboard or other suitable 50 material is cut and scored as shown in Figure 1, in which A is the blank for the cover, and B the blank for the body of the carton, and the two parts are substantially identical, except that the display flap for 55 one end of the box is not scored, while the

tongue for the end of the cover portion is scored.

It will also be noted that the two portions A and B are integrally connected by a strip C, and that the distance between the 60 contiguous end flaps of the two parts is sufficient, so that when two complete blanks are cut out side by side the space between provides a small card sized piece of rectangular shape, which is thus not waste material and can be used for small signs. 65

The portion of the blank for the body of the carton is formed with score lines 1, 2, 3 and 4 to form the bottom 5 of the box, with side flaps 6 and 7 to form the sides; 70 each side flap is provided with end flaps 8, 9 and 10, 11, adapted to overlap to form the ends and each end flap is formed with an interlocking slit α , so that these end pieces can be locked together to form the 75 ends.

In the same way, the portion 12 of the cover portion is formed for the top of the cover with side flaps 13 and 14 for the sides to which are attached the interlocking end flaps 15, 16, 17 and 18 for the ends of the 80 cover adapted to be interlocked with the slits b.

For the cover, the top is provided with an end flap 23, scored at 24 to fold over the 85 end flaps 15, 16 when interlocked and this end piece 23 has a narrow tongue 25 to fold down along the inside of the top to form a secure end structure for the cover.

The two blanks A and B are connected 90 by the strip C, scored at 26 and 27 to form end reinforcements 19 and 20 for the interlocked end flaps of the box and cover, respectively. This strip is also scored with lines 28, 29, and 30 to permit of bringing 95 the cover around under the box for display purposes as will be described. The other end of the box is also provided with an end reinforcement 31, to which is attached a display flap 32. 100

The two portions of the blanks A and B being separated from each other, and only connected by the long strip C, the box and cover are very easily and quickly set up. So distinct are they that one operative can be setting up the box at the same time that another operative is at work with the cover. 105

For the body of the box, the sides 6 and 7 are turned up and the ends 8, 9, and 10, 11 folded across and interlocked, the flap 31 110

being extended upwardly on the inside of the interlocked ends while the flap 20 remains outside the interlocked ends.

The same method is pursued for the cover.

- 6 The sides 13 and 14 are folded up and the ends 15, 16 and 17, 18 interlocked in this case with the flaps 23 and 19 on the outside. For the outer end of the cover, the flap 23 is folded over the interlocked flaps
- 10 15 and 16 and the tongue 25 is tucked in at the bottom of the cover portion.

The box is then ready for packing. When packed with the goods, the cover is turned over and pushed down over the box body, 15 the section 21 folding inside the cover on the score line 30, the other sections of the strip C folding over the contents of the box and the display flap folding inside on top of the goods.

- 20 When it is desired to display the goods, the cover is lifted off the box at the unattached end and carried down around the other end of the box, turned over and the attached end of the box brought to the opposite end of the cover on the inside, so that the free end of the box will rest upon the attached end of the cover. The box will then rest with one end raised to display the contents, the display flap being 25 folded outwardly. To close the box, the display flap is folded down and the action reversed. The manipulation is so simple that the cover either in placing it under the box for support or bringing it back to cover 30 position does not have to be fully removed from the box.

The benefits and advantages of my construction will be obvious from the foregoing description.

- 40 As the container portion and the cover portion are, so to speak, independent of each other, the carton can be set up and ready for use in the least possible time and with the greatest ease and convenience.
- 45 The container can also be packed with the goods without any interference with the cover. When the cover is removed for display of the box contents it can be turned directly under the box by a single movement and with a reverse movement brought back to cover the box.

It will also be obvious from an inspection of the blank as shown in Figure 1 that there is practically no waste of material in cutting the blank.

Having thus described my invention, what I claim as new and desire to secure by Letters Patent, is:—

- 50 1. A carton formed from a single blank of suitable material cut and scored to form body and cover portions of bottom, sides, and ends, with said two portions integrally

connected longitudinally by a strip of the material extending between the adjacent ends of the top and cover when the carton 65 is closed and scored to permit folding with the cover and container both upright as the carton is set up, whereby the cover may enclose the container and may be removed therefrom and turned to hold the container 70 in display position.

2. A carton formed from a single blank of suitable material cut and scored to form similar body and cover portions of bottom, sides, and ends, with said two portions integrally connected longitudinally by a strip of the material extending between the adjacent ends of the top and cover when the carton is closed and scored to permit folding with the cover and container both upright 75 as the carton is set up, whereby the cover may enclose the container and may be removed therefrom and turned to hold the container in display position.

80 3. A carton formed from a single blank 85 of suitable material cut and scored to form two distinct portions, one constituting the body of the carton and the other the cover, each portion having a bottom of approximately the same size and shape with side 90 flaps to form the side walls, and extensions from the side flaps to form ends, with an integral connecting strip between the bottoms of each portion extending between the adjacent ends with the cover and container 95 both upright as the carton is set up to permit the cover to enclose the body portion and to be reversed to hold the container in display position.

4. A carton formed from a single blank 100 of suitable material cut to form two complete open boxes, each having bottom, sides and ends, and a bendable interconnecting strip integral with both boxes but forming 105 no part of either box and extending between the adjacent ends of the two boxes whereby both boxes when separated shall open upwardly and an end flap for the container for display advertising.

5. A carton formed from a single blank 110 of suitable material cut to form two complete open boxes, each having bottom, sides and ends, and a bendable interconnecting strip integral with both boxes but forming 115 no part of either box, and extending between the adjacent ends of the boxes, said interconnecting strip being creased to form folds adapted to guide the one box into a position within the other with one box resting at one end on the end wall of the other and with the interconnecting strip enclosed between the two boxes and an end flap for the container for display advertising.

LEVERETT D. CAMPBELL.
